UNITED STATES PATENT OFFICE.

GEORGE W. THOMPSON, OF SPRINGFIELD, MISSOURI, ASSIGNOR OF THIRTY-TWO ONE-HUNDRED-AND-TWENTY-EIGHTHS TO WILLIAM B. SANFORD, TWENTY-FOUR ONE-HUNDRED-AND-TWENTY-EIGHTHS TO DOUGLAS J. LANDERS, TWENTY-ONE ONE-HUNDRED-AND-TWENTY-EIGHTHS TO WILLIAM A. McATEE, TWELVE ONE-HUNDRED-AND-TWENTY-EIGHTHS TO ALPHONSO B. LOVAN, TWELVE ONE-HUNDRED-AND-TWENTY-EIGHTHS TO GEORGE W. YOUNG, AND THREE ONE-HUNDRED-AND-TWENTY-EIGHTHS TO WILLIAM T. SHORES, ALL OF SPRINGFIELD, MISSOURI, AND SIX ONE-HUNDRED-AND-TWENTY-EIGHTHS TO CLARENCE H. NICHOLS, OF NEW YORK, N. Y.

ACETYLENE-GAS GENERATOR.

1,274,212.

Specification of Letters Patent. Patented July 30, 1918.

Application filed December 8, 1917. Serial No. 206,165.

To all whom it may concern:

Be it known that I, GEORGE W. THOMPSON, a citizen of the United States, residing at Springfield, Greene county, Missouri, have 5 invented a new and useful Acetylene-Gas Generator, of which the following is a specification.

This invention relates to acetylene gas generators.

10 An object of the invention is to provide an acetylene gas generator comprising two receptacles, each of which is arranged to contain a gas forming material which when brought together generate the gas, in combination with mechanism arranged to operate automatically to deliver one of the gas forming materials from the receptacle in which it is contained into the other receptacle in which the gas is generated.

20 Another object of the invention is to provide an apparatus for generating gas comprising two receptacles arranged to contain gas forming materials which when brought together will generate gas, and a device 25 movable in one direction by the pressure of the gas to a position to receive the gas forming material from one of said receptacles, and movable in the opposite direction by independent means to a position to deliver 30 the gas forming material into the other receptacle in which the gas is generated.

With the foregoing and other objects in view, I have illustrated my invention in the accompanying drawing, in which—

35 Figure 1 is a view illustrating in section the mechanism for delivering the gas forming material from one of the receptacles into the other.

Fig. 2 is a sectional view on the line 2—2 40 of Fig. 1.

The receptacle 1 is arranged to contain one of the gas forming materials, such as water, and is provided with an opening through which the material may be delivered into the receptacle, said opening being normally closed by a removable plug or closure 2. The receptacle 1 may be regarded as the generating tank and has an outlet pas-

sage 3 through which the gas is conducted to any desired point of use. 50

The other receptacle 4 is arranged to contain another gas forming material which when delivered into the gas forming material in the receptacle 1 results in the generation of gas. The receptacle 4 is provided with a filling opening having a removable closure 5. The lower walls of the receptacle 4 are inclined so that the gas forming material within the receptacle will be discharged through the central opening. 60

The mechanism for delivering the gas forming material from the receptacle 4 into the receptacle or generating tank 1 is automatic in operation. This mechanism is arranged to operate so that when the gas within the receptacle 1 becomes reduced to or below a predetermined minimum an additional quantity of the gas forming material will be transferred from the receptacle 4 into the generating tank 1. 70

A chamber 6 is secured to the generating tank 1 and supports the receptacle 4. The chamber 6 is provided with an opening 7 through its upper wall in communication with the opening through the bottom wall of the receptacle 4, so that the gas forming material contained in the receptacle 4 may pass into the chamber 6. The bottom wall of the chamber 6, near one end thereof, has an opening 8 which registers with a similar opening through the top wall of the generating tank. The openings 7 and 8 are thus out of alignment so that it is necessary for the gas forming material to move or be moved laterally in the chamber 6 in order 85 to pass or be delivered through the opening 8 into the generating tank.

An axially movable carrier 9 is mounted within the chamber 6 and is provided with a circumferential groove or chamber 10 90 which in one position of the carrier, as illustrated in Fig. 1, registers with the opening 7 and receives a quantity of gas forming material from the receptacle 4. When the carrier 9 is moved axially the groove or chamber 10 is brought into registration with

the opening 8 through which the gas forming material contained in the groove 10 drops into the generating tank 1, thus bringing together quantities of the gas forming material and causing the generation of gas 5 in the generating tank.

The device for moving the carrier 9 from the position illustrated in Fig. 1, in which the gas forming material is received from 10 the receptacle 4, to the position in which the gas forming material is discharged into the generating tank comprises a spring 11 encircling a rod 12 connected to the carrier 9 and extending through one end of the 15 chamber 6. One end of the spring 11 bears against an abutment 13 in connection with the chamber 6 and the opposite end of the spring bears against an abutment 14 attached to the rod 12. Thus when the carrier 20 9 is in the position illustrated in Fig. 1, in which the gas forming material is being received from the receptacle 4, the spring 11 is under compression and at the proper time will expand and move the carrier 9 from the 25 receiving position to position for discharging the gas forming material into the generating tank.

The pressure against opposite ends of the carrier 9 is equalized. In order to maintain the pressure on opposite ends of the carrier at equilibrium I have found it practicable to admit pressure into the chamber 6 on opposite ends of the carrier 9. In order to admit pressure at one end the opening 8 is 30 arranged to admit gas into the chamber 6 between the end of the carrier 9 and the end wall of the chamber when the carrier 9 is in any position. In order to admit pressure into the chamber 6 at the opposite end of 35 the carrier a pipe 15 is provided, the same constituting a passage from the tank 1 into the chamber 6. Thus the pressure on opposite ends of the carrier 9 is at all times equal, being the same as the pressure within the 40 generating tank.

After the carrier has been moved by the spring 11 to position for discharging the gas forming material into the tank 1 it is necessary to return the carrier to its receiving 45 position. This is accomplished by the pressure of the gas generated in the tank 1. For this purpose the rod 12 is provided with a piston 16 mounted within a piston chamber or cylinder 17 at one end of which there 50 is a passage 18 for admitting pressure from the generating tank 1 into the cylinder 17. Thus when the pressure in the generating tank rises beyond a predetermined limit the piston 16 will be moved by the gas pressure, 55 thereby moving the rod 12 and the carrier 9 in opposition to the power of the spring 11. The carrier is moved in the manner described to position in which the groove 10 registers with the opening 7, as shown in 60 Fig. 1, and the carrier will be retained in 65

that position by the pressure of the gas until a quantity of the gas is withdrawn from the generating tank. When the pressure of the gas against the piston 16 is less than the power of the spring 11, as when the gas 70 is withdrawn from the generating tank, the spring 11 will expand and move the carrier axially to position to discharge an additional quantity of the gas forming material into the generating tank, after which the operation 75 above described is repeated.

In order to make possible the above described operation of the piston 16, it is necessary to provide means for permitting the passage of air into and out of the cylinder 17 on the side of the piston 16 opposite from the passage 18. For this purpose there is provided a valve controlled passage 19 in which the valve is of usual construction so that when in one adjustment the passage is 80 open and when in another adjustment the passage is closed. In order to enable the mechanism to operate as required to deliver the gas forming material into the generating tank the valve in the passage 19 is 85 placed in open position to permit the air to pass freely into the chamber 17 when the piston is moved under the impulse of the spring 11; and to permit the air to pass out of the chamber 17 when the piston 16 is 90 moved in the opposite direction by the pressure of the gas.

In order to prevent operation of the mechanism for delivering the gas forming material into the generating tank it is only 100 necessary to place the valve in the passage 19 in closed adjustment so that the piston 16 can not operate under ordinary conditions.

I am aware that the mechanism for operating the carrier for delivering the gas forming material into the generating tank may be varied, and that other features of the invention may be modified in order to adapt the invention for the various uses to which 110 it may be applied. I contemplate such variation, and do not restrict myself to unessential features, but what I claim and desire to secure by Letters Patent is:—

1. An acetylene gas generator, comprising 115 a generating tank arranged to contain one of the gas forming materials, a separate receptacle arranged to contain another gas forming material, a chamber, a carrier in said chamber movable to one position to receive the gas forming material from said receptacle and movable to another position to discharge the gas forming material into the generating tank, passages from said generating tank for admitting gas into said chamber at opposite ends of said carrier, whereby said carrier is maintained in a balanced 120 position as to the pressure in the generating tank, a cylinder, a rod in connection with said carrier extending into said cylinder, a 125

130

- piston attached to said rod in said cylinder, a passage from said generating tank for admitting pressure into said cylinder at one end of said piston to actuate said carrier to 5 position to receive gas forming material from said receptacle and a spring coöperating with said rod for moving said piston to position to discharge the gas forming material into the generating tank.
- 10 2. An acetylene gas generator, comprising a generating tank arranged to contain one of the gas forming materials, a separate receptacle arranged to contain another gas forming material, a chamber, a passage from said 15 receptacle for delivering gas forming material into said chamber, a passage from said chamber for admitting the gas forming material therefrom into the generating tank and arranged to admit pressure into 20 the chamber against one end of the carrier therein, a carrier in said chamber movable to one position to receive the gas forming material from the passage from said receptacle and movable to another position to 25 discharge the gas forming material into the passage to the generating tank, a passage for admitting gas from the generating tank into said chamber at the opposite end of the carrier whereby said carrier is maintained 30 in a balanced position as to the pressure in the generating tank, a cylinder, a rod in connection with said carrier extending into said cylinder, a piston attached to said rod in said cylinder, a passage from said generating tank for admitting pressure into said cylinder at one end of said piston to cause 35 said piston to actuate said carrier to position to receive gas forming material from said receptacle, and a spring coöperating 40 with said rod for moving said piston to position to discharge the gas forming material into the passage to the generating tank.
3. An acetylene gas generator, comprising a generating tank arranged to contain one 45 of the gas forming materials, a separate receptacle arranged to contain another gas forming material, a chamber, a passage from said receptacle for delivering gas forming material into said chamber, a passage from 50 said chamber for admitting the gas forming material therefrom into the generating tank and arranged to admit pressure into the chamber against one end of the carrier therein, a carrier in said chamber movable 55 to one position to receive the gas forming material from the passage from said receptacle and movable to another position to discharge the gas forming material into the passage to the generating tank, a passage 60 for admitting gas from the generating tank into said chamber at the opposite end of the carrier whereby said carrier is maintained in a balanced position as to the pressure in the generating tank, a cylinder, a rod in connection with said carrier extending into said 65
- cylinder, a piston attached to said rod in said cylinder, a passage from said generating tank for admitting pressure into said cylinder at one end of said piston to cause 70 said piston to actuate said carrier to position to receive gas forming material from said receptacle, and an actuator in connection with said rod for moving said carrier to position to discharge the gas forming material into the passage to the generating tank.
4. An acetylene gas generator, comprising a generating tank arranged to contain one of the gas forming materials, a separate receptacle arranged to contain another gas 80 forming material, a chamber, a passage from said receptacle for delivering gas forming material into said chamber, a passage from said chamber for admitting the gas forming material therefrom into the generating tank and arranged to admit pressure into the chamber against one end of the carrier therein, a carrier in said chamber movable to one position to receive 85 the gas forming material from the passage from said receptacle and movable to another position to discharge the gas forming material into the passage to the generating tank, a passage for admitting gas from the generating tank into said chamber at the 90 opposite end of the carrier whereby said carrier is maintained in a balanced position as to the pressure in the generating tank, a cylinder, a rod in connection with said carrier extending into said cylinder, a piston 95 attached to said rod in said cylinder, a passage from said generating tank for admitting pressure into said cylinder at one end of said piston to cause said piston to actuate said carrier to position to receive gas 100 forming material from said receptacle, means for varying the amount of pressure required to move said piston as aforesaid, and a spring coöperating with said rod for moving said piston into the passage to the 105 generating tank.
5. An acetylene gas generator, comprising a generating tank arranged to contain a gas forming material, a separate receptacle arranged to contain another gas forming 110 material, a chamber, a passage from said receptacle into said chamber, a carrier in the chamber arranged to receive the gas forming material from the receptacle, a passage from the chamber into the generating tank through which the gas forming material is discharged from the carrier into the generating tank, said passage admitting pressure from the generating tank into the chamber at one end of the carrier, a passage from and admitting pressure from the generating tank into said chamber at the opposite end of the carrier, whereby said carrier is maintained in a balanced position 115 as to the pressure in the generating tank, a 120
- 60

device for actuating said carrier to position to receive gas forming material from said receptacle, and a separate device for actuating said carrier to position to discharge the 5 gas forming material into the passage to the generating tank.

6. An acetylene gas generator, comprising a generating tank arranged to contain a gas forming material, a receptacle arranged 10 to contain another gas forming material, a chamber, a carrier in said chamber movable to one position to receive gas forming material from said receptacle and movable to another position to discharge the gas forming 15 material into the generating tank, passages opening into said chamber at opposite ends of said carrier, whereby pressure from the generating tank is admitted into said chamber and said carrier is maintained in 20 a balanced position as to the pressure in the generating tank, a device actuated by the pressure in the generating tank for moving said carrier to position to receive gas forming material from said receptacle, 25 means for varying the amount of pressure required to move said device, and a separate actuator for moving said carrier to position to discharge gas forming material into the generating tank.
- 30 7. An acetylene gas generator, comprising a generating tank arranged to contain a gas forming material, a receptacle arranged to contain another gas forming material, a chamber, a carrier in said chamber 35 movable to one position to receive gas forming material from said receptacle and movable to another position to discharge the gas forming material into the generating tank, passages opening into said chamber at opposite 40 ends of said carrier, whereby pressure from the generating tank is admitted into said chamber and said carrier is maintained in a balanced position as to the pressure in the generating tank, a device actuated by 45 the pressure in the generating tank for moving said carrier to position to receive gas forming material from said receptacle, and a separate actuator for moving said carrier to position to discharge the gas forming 50 material into the generating tank.
- 55 8. An acetylene gas generator, comprising a generating tank arranged to contain a gas forming material, a receptacle arranged to contain another gas forming material, a chamber, a carrier in said chamber movable to one position to receive the gas

forming material from said receptacle and movable to another position to discharge the gas forming material into the generating tank 60 into said chamber at opposite ends of said carrier, whereby the carrier is maintained in a balanced position as to the pressure in the generating tank, a cylinder, a piston in said cylinder, a rod connecting said piston 65 with said carrier, a passage for admitting pressure into said cylinder at one end of the piston, whereby said carrier is actuated by the pressure in the generating tank to position to receive gas forming material from 70 said receptacle, a valve device in connection with said cylinder adjustable to vary the amount of pressure required to move said piston, and a spring which is placed under compression by the movement of said piston 75 as aforesaid and which expands to move said carrier to position to discharge gas forming material into the generating tank when the pressure of the gas against said piston becomes less than the power of said 80 spring.

9. An acetylene gas generator, comprising a generating tank arranged to contain a gas forming material, a separate receptacle arranged to contain another gas forming material, a chamber, a carrier in said chamber, passages from said generating tank into said chamber at opposite ends of said carrier whereby said carrier is maintained in a balanced position as to the pressure in the generating tank, a passage from said receptacle into said chamber, a cylinder, a piston in said cylinder, a rod connecting said piston and said carrier, a passage for admitting gas from said generating tank 90 into said cylinder at one end of said piston whereby said piston is actuated to move said carrier to position to receive gas forming material from said receptacle, a valve in connection with said cylinder for 95 varying the resistance to the movement of said piston, and a spring in connection with said rod compressed by the movement of said rod by said piston as aforesaid, and arranged to actuate said rod and thereby 100 said carrier to position to discharge gas forming material into the generating tank when the pressure of the gas against the piston becomes less than the power of the 105 spring.

GEORGE W. THOMPSON.
